BEET-CUTTING MACHINE.

1,075,624.

Specification of Letters Patent.

Patented Oct. 14, 1913.

Application filed November 4, 1912. Serial No. 729,496.

To all whom it may concern:

Be it known that I, ROBAH J. BINKLEY, a citizen of the United States, residing at Chino, in the county of San Bernardino 5 and State of California, have invented certain new and useful Improvements in Beet-Cutting Machines, of which the following is a specification.

My invention relates to improvements in 10 high capacity machines to be used in sugar refineries for cutting sugar beets into shreds or cossettes. After being cut, these shreds are soaked in the liquid of diffusion tanks where as much of the sugar as possible is 15 dissolved out from the shreds in the time that is practicable for leaving the shreds in the tanks.

The general object of this invention is to 20 provide a simple and efficient mechanical combination which can perform its functions well, even when the demands of large scale sugar refining are thrown upon it; and the principal specific object of the invention is to efficiently produce long shreds having 25 thin leaves joined substantially, like in a U or V, and to produce such shreds in abundance and almost to the exclusion of shreds having other shaped sections. When shreds of this character are thrown into the diffusion 30 tanks the liquid can act upon the thin leaves from both sides of each leaf, and in a given time can therefore abstract the sugar to a greater degree of thoroughness than was possible with the relatively thicker solid 35 shreds having the various rectangular sections that were cut by most of the former machines used in large sugar refineries. By adopting the invention considerable annual savings can be effected, both by increasing 40 the amount of sugar that may be abstracted from a pound of shreds in a given time so that less sugar is cast to waste in the soaked shreds, and also by expediting the abstracting operations in the diffusion tanks.

Another object of the invention is to secure 45 perfect control over the thickness of each individual shred instead of depending merely on changing the average thickness of all the shreds taken together. Adjusting 50 the thickness of the shreds is important, because of the different percentages of sugar contained in beets grown in different fields and under different circumstances, and because the shreds from beets thus differing

in sugar content should be of different thicknesses, so that the liquid in the diffusion tanks can withdraw the sugar to about the same degree of thoroughness from all beets irrespective of their sugar content. This being the case, it is obviously advantageous 60 to have control over the thickness of practically each individual shred rather than only over the average thickness of all the shreds taken together.

Another advantage of my invention is 65 that the corrugated knife edges become so disposed with relation to the corrugated counter-plate or guide-bar that a greater portion of the knife edge is exposed to the beet and foreign matter in the drum, thus 70 providing for the severance of grass and rags which sometimes enter the machine with the beets. The ability of my machine to readily cut this foreign matter avoids the 75 delay and inconvenience occasioned by the clogging of the old machines under similar circumstances.

The accompanying drawings illustrate the invention.

Figure 1 is a transverse vertical section 80 of the machine embodying my invention, taken on line x^1-x^1 of Fig. 2, and looking in the direction of the arrows. Part of the drum and stationary casing have been broken away to show internal parts. Fig. 85 2 is a vertical axial section of the machine taken on line x^2-x^2 , of Fig. 1, part of the outer upper portion of the drum being shown. This view is somewhat diagrammatic, but indicates the alinement between 90 the corrugations of the knives and the corrugations of the guide-bar, which alinement extends around the whole periphery of the drum. Fig. 3 is an enlarged detail view showing an ordinary section plate provided 95 with knives and with my corrugated guide-bars, the plate being in section. Fig. 4 is an enlarged plan showing the details of one knife and its adjacent guide-bar in their actual relative positions, and the arrow indicates the direction in which these elements move during normal cutting. Fig. 5 is a section on line x^5-x^5 , Fig. 4, showing the corrugations on the knife. Fig. 6 is a section on line x^6-x^6 , of Fig. 4, showing 105 the corrugations of the guide-bar, and the edge of one of the next advancing knives being indicated above one side of the guide-

bar. Fig. 7 shows a beet as cut by a corrugated knife, said beet resting on the corrugations of my improved guide-bar. The dotted lines show where the next succeeding corrugated knife edge lies, and indicates how the corrugations on the guide-bar hold the corrugations on the beet face in exact alinement with the corrugations of the next knife. The beet is supposed to be in the process of transfer over the corrugated guide-bar to the next knife. Fig. 8 is a view showing the sectional shape of the V or U-shaped shreds cut by machines embracing my invention. Fig. 9 is a view showing some of the sectional shapes of shreds usually cut by prior rotating drum machines. Fig. 10 is a plan view of two consecutive knives, and a guide-bar between the same, both the knives and guide-bar in this figure illustrating a further improved modification over the form shown in Fig. 4. The arrow indicates the direction in which the construction travels during the normal cutting operation. Fig. 11 is a sectional elevation through line $\alpha\alpha'$ of Fig. 12 and shows the details of my further improved modified guide-bar shown in Fig. 10. Fig. 12 is a front elevation of a fragment of the same improved guide-bar.

Having above described the basic principles and novelty upon which this invention rests I will now describe the general construction of a high capacity rotating-drum machine, and will particularly show and describe the new corrugated adjustable and rotatable guide-bars whereby the advantages of my invention are attained.

In general, 1 is a knife-supporting drum comprising the rear circular flange or web 2 and peripheral bars 3. The rear web 2 is unperforated except at the central hub 4 through which passes the supporting and driving shaft 5, the hub and drum being fastened to the same by the set-screw 6. The driving shaft is supported on one side by the bearing 7, mounted on a suitable standard 8, and on the other side by bearing 9 built integral with the hopper 10. Surrounding the periphery and fitting up close to the forward side of the drum, is a stationary guard or cover plate 11 provided adjacent the hopper with feed opening 12 through which the beets may pass from the hopper into the drum. The purpose of this guard plate is to protect the operator from the revolving parts, and also to prevent the beets from falling out of the drum during operation.

Upon the inner face of the drum, and practically comprising a part of the drum, are mounted section plates 13 fastened by bolts 14 which pass through the rear flange 2, and hold the section plates against longitudinal motion in the direction parallel to shaft 5. The outer periphery of said plates

being longer than the inner periphery, the complete circle of plates coöperate with each other on the arch principle to support themselves radially, and prevent any one section from falling toward the center. The peripheral bars 3 of the drum lie adjacent the abutting ends of the section plates and will prevent the same from flying away from the center. By this means the section plates are bound together so as to form a strong rigid shell or drum, the plates being covered on their outer side only by the narrow bars 3.

Upon the inner surface of the section plates are carried the cutting knives 15 and counter-plates or guide-bars 16. By referring more particularly to Fig. 3, the means of mounting these knives and guide-bars may be clearly seen. The knives are rigidly supported on seats 17 of the section plate, through which seats pass suitable apertures 18. The bolts 19 pass through these apertures and are provided at their upper ends with flat wedge-shaped heads 20 adapted to lie in the wedge-shaped grooves 21 of the knife. When the nut 22 is screwed tightly onto the other threaded end of the bolt, the said wedge-shaped heads will bind the knife tightly to its seat 17. The grooves 21 extending longitudinally of the knife, will permit some adjustment of the same along the seat 17.

The concave seat 23 on the section plate is adapted to support the guide-bar 16 which has a similar and coöperating convex seat 26, the section plate being provided adjacent the seat 23 with a series of elongated apertures or slots 24. The guide-bar is provided with series of studs 27, one passing through each of the elongated slots 24, and the lower or outer extremities of the studs 105 being provided with washers 28 which are held in place by nuts 29.

In the region approximately between the knife 15 and the guide-bar 16, the section plate is provided with a wide slot 30 through which the shreds or cossettes are discharged from the inner side of the drum to its outer side after having been cut by the knives.

The detailed construction of the knives and guide-bars may be more readily understood by reference to Figs. 4, 5, 6, 10, 11 and 12. The cutting edge 31' of the knife is at the extremity of the corrugated or fluted plane 31, the crests and troughs of said corrugations running substantially perpendicular to the knife edge 31'. From the trough of the corrugations, and extending downward are the cutting projections 32, Fig. 5, serving to cut the beet into shreds or cossettes rather than into corrugated sheets as might be the case if the said projections were omitted.

In prior machines of the character described the upper or guiding faces of the guide-bars 16 were flat, but the purposes of

my invention are attained principally by providing the guiding face of said guide bars with corrugations 33 similar to the corrugations 31 of the knife, said corrugations on the guide-bar being alined trough for trough and crest for crest with the corrugations of the knife—see Figs. 2, 4, 6 and 10. This alined relation is maintained not only between the corrugations of one knife and its 10 adjacent guide-bar, but is continuous over all the knives and guide-bars around the whole drum, as indicated in Fig. 2. It is advantageous that both longitudinal sides of the corrugations 33 of the guide-bar be 15 beveled off to an apex 33'. As will be better understood hereinafter this permits the beet to be taken up onto the guide-bar gradually and without bruising. It also permits the guide-bar to be reversed so that its both 20 sides may be used.

When the nut 29 is loosened upon the stud 27, the guide-bar 16 may be rocked upon seat 23, thereby raising and lowering the extreme guiding edge 34, Fig. 3, of the 25 bar with respect to the cutting edge 31' of the knife. It is by this means that the adjustment of the former flat-faced guide-bars is attained and the adjustment of my novel corrugated guide-bars may be attained, in 30 the same manner. It will be understood that the higher the guiding edge 34 is raised, the thinner will be the shred of beet cut by the edge of the knife, so that the adjustment for shred thickness depends on the 35 point at which nut 29 is fastened.

Referring now to some other parts which are used in these machines, a stationary apron 35, Fig. 1, is seen to project outward horizontally and downwardly from the 40 guard-plate 11, said apron extending across the full width of the drum. The purpose of this apron is to arrest the beets and to hold them quiet and firm against the rolling influence of the revolving drum. In this 45 manner the stationary apron absolutely discourages any interference with the operation whereby the corrugations in the guide-bar are delivering and guiding the cut beets onto the successive knives with the corrugations previously cut into said cut beets in exact alinement with the corrugations of the 50 next succeeding knives. If desired, some suitable conveying means 36 may also be provided beneath the drum, said conveying 55 means serving to receive the shreds discharged through apertures 30, and to convey said shreds away from the machine. A driving pulley 38 may also be mounted on shaft 5, and power for rotating the drum 60 may be imparted through belt 37. The turning force is imparted to the drum through shaft 5 by any suitable means such as belt 37 acting on pulley 38.

In using the machine embodying my invention, the beets are emptied upon hopper

10 and roll by their own weight through opening 12 into the revolving drum 1, where the knives commence their shredding action immediately. Fig. 7 shows a beet as cut by a knife, the cut surface 39 having corrugations corresponding to those of the knife which cuts it. After passing off the corrugated surface of the knife, the beets may shift while gliding over the flat uncorrugated portion 41 of the knives, Fig. 4, but the corrugations cut into the beets will next drop upon the alined corrugations 33 of the following guide-bar. The beets will automatically be drawn into a position relative to the corrugated bar 16 as shown in Fig. 7, 20 and the corrugations in said bar will then hold the beet from further shifting, so that the beet will be delivered against the next knife edge with the corrugations previously cut into the beet in exact alinement with the corrugations of said knife edge. In this manner the next knife will cut into the beet along the dotted line 40, Fig. 7, thus producing the V- or U-shaped shreds shown in Fig. 8. The thickness through the 25 leaves of these shreds will depend on the adjustment of the guide-bar as previously explained.

The successive knives and guide-bars being alternately placed in series and having 30 their corresponding corrugations all alined, the beet in effect passes from knife to bar to the next knife and next bar, etc., its corrugated cut face always being brought and held in line with the corrugations of the 35 knives by the corrugations of the guide-bars. Under these conditions the machine will operate to uniformly produce shreds having the U or V-shape shown in Fig. 8. This shape is not secured unless the guide-bar is provided with my corrugations, and the successful uniform cutting of such shreds is secured because the apron is stationary within the revolving drum whereby the beets are held quiet, and the alining 40 action of the guide-bars goes on undisturbed. When finally the shreds reach the diffusion tank, the rapidity with which the liquid there will abstract their sugar depends on the amount of surface they present. With 45 my V section, a relatively great surface per pound of shreds is secured and the diffusion process is accordingly hastened. The thoroughness with which the liquid will abstract the sugar from the shred will also 50 depend on its thickness and by proper adjustment of the guide-bar the leaves of the V section may be exceedingly thin, as compared with the shreds of Fig. 9 produced in the old machines.

The detailed advantages secured by my invention have been heretofore described and further reference thereto need not be made here.

cated side by side before each guide-bar, so that if one knife is nicked or broken, both need not be replaced. The value of the knives being considerable, this feature is important. The usual machines are also provided with eight section plates, each being provided with three guide-bars and three sets of knives, but obviously the number of section plates, and the number of knives and guide-bars on each section plate may be varied according to the judgment of the designer, and such variation does not affect the invention herein disclosed.

The knife shown in Fig. 4 represents an old form ordinarily used in prior rotating drum beet cutters. It gives perfectly satisfactory service in connection with this invention, but it seems possible that for the purposes required it may be improved somewhat. As the cut beet passes from the corrugations 31 toward the rear of the blade Fig. 4, the beet encounters the uncorrugated knife portion 41, and in this region a beet might at infrequent intervals slip unusually far so that its corrugated face might not be caught up properly on the corrugations of the next succeeding guide-bar. To avoid this possibility and to make the passage of the cut corrugated beet face even more positive from the cutting edge of the knife to the next succeeding guide-bar, etc., I prefer to continue the corrugations 31 along the whole length of the knife to its rear edge 42 as shown in Fig. 10. It will be seen then that the slipping of the beet is practically impossible and that the corrugations on its cut face cannot become disarranged with respect to those of the cutters or guides. Of course all the advantages, hereinbefore carefully described, of holding the beets quiet by having the apron stationary in the revolving drum operate to give the same, or even greater, satisfaction with this form of knife as with the form of knife shown in Fig. 4. Again it may be seen from Fig. 4 that small beets, or the thin flake remaining after a large beet has been almost completely cut up, may sometimes be driven right out through the slit between the cutting edge 31' of the knife and the adjacent side of the guide-bar. When this condition obtains the vertical knife cutting portions 32 may be missed and the beet will issue in the form of a thick flake rather than a V-shaped cossette. To avoid this objection I have invented the novel guide-bar shown in Figs. 10, 11 and 12, which has suitable projections 43 all along both its longitudinal sides the said projections being adapted to extend beneath the corrugations as indicated in Fig. 10. By this means the perpendicular opening between the knife edge 31' and the body of the guide-bar is practically blocked and the beet cannot be jammed or dropped out through same. The beet is thus always spared from

the aforesaid jamming and must always pass the knife in such manner as to be cut into perfect V-shreds by the vertical cutting portions 32.

Fig. 11 shows the upper surface of the transverse corrugations 33 beveled on both longitudinal sides toward the apex 33'. The double bevel and the double row of projections 43, one on each side of the guide-bar, adapts same to be reversible so that after one side of the bar becomes unsatisfactory for purposes of guiding the beet against the cutting edge the bar may be reversed so as to bring its other side into operative position. The projections 43 may also be beveled off at their outer extremities 44, this being desirable in order to permit the V-shreds to easily pass off these projections. In other respects the guide-bar of Fig. 11 is formed and adjusted similar to that shown in Fig. 3.

I claim:—

1. In combination, a revoluble drum adapted to hold beets, and said drum having its axis of rotation substantially horizontal, corrugated knives mounted around the internal periphery of said drum, and corrugated guide bars for said knives, said guide bars being also mounted around the internal periphery of said drum, and the crests of the guide bar corrugations being substantially aligned with the crests of the knife corrugations, so that substantially U-shaped shreds may be cut.

2. In combination, a revoluble drum adapted to hold beets, said drum having its axis of rotation substantially horizontal, corrugated knives mounted around the internal periphery of said drum, corrugated guide bars for said knives, said guide bars being also mounted around the internal periphery of said drum, the crests of the guide bar corrugations being substantially aligned with the crests of the knife corrugations so that substantially U-shaped shreds may be cut, and a stationary apron in said drum for holding said beets substantially quiet within the drum.

3. In combination, a revoluble drum adapted to hold beets, said drum having its axis of rotation substantially horizontal, corrugated knives mounted around the internal periphery of said drum, corrugated guide bars for said knives, said guide bars being also mounted around the internal periphery of said drum, the crests of the guide bar corrugations being substantially aligned with the crests of the knife corrugations, so that substantially U-shaped shreds may be cut, and said corrugated guide bars being adjustably mounted with respect to the knife edges so that the thickness substantially of each individual shred may be controlled, and a stationary apron in said drum for holding the beets substantially quiet in the drum.

4. In a beet cutter, rotatably mounted knives and guide-bars, said knives and guide-bars being alternately placed with respect to each other, corrugations on said 5 knives and guide-bars, the corrugations of the knives being alined with the corrugations of the guide-bars, and projections on said guide-bars adapted to extend beneath the corrugations of said knives.
- 10 5. A guide-bar for rotary beet cutters, said guide-bar having transverse corruga-
- tions, said guide-bar being beveled along both longitudinal sides, and projections from the side of said bar adapted to secure the uniform cutting of cossettes. 15

In testimony whereof I have hereunto set my hand at Chino, California, this 26th day of October, 1912.

ROBAH J. BINKLEY.
